RAILWAY TRAFFIC CONTROLLING APPARATUS

Paul P. Stoker, Joliet, Ill., assignor to The Union Switch and Signal Company, Swissvale, Pa., a corporation of Pennsylvania

Application September 19, 1942, Serial No. 458,931

3 Claims. (Cl. 246—114)

My invention relates to railway traffic controlling apparatus, and more particularly to apparatus for governing traffic at grade crossings and similar hazards.

A railroad grade crossing or similar hazard is usually provided with signals, derails, train stops or a combination of such devices for governing traffic thereover. These devices are frequently controlled automatically, and a track circuit is commonly used for accomplishing such automatic control. On electrified roads, such as street car lines, track circuits involve costs that may be prohibitive. Also the closeness at which street cars are operated may make track circuits undesirable.

Accordingly, a feature of my invention is the provision of railway traffic controlling apparatus incorporating novel means for automatic control of traffic governing devices at grade crossings and other hazards, and wherewith track circuited track sections are not required.

Another feature of my invention is the provision of novel automatic grade crossing control apparatus that requires the same number of cars be counted out of a crossing control section of one of the roads as are counted into the control section before the crossing is released for use by the other road.

Another feature of my invention is the provision of novel means for control apparatus at grade crossings and similar points wherewith restoration of a traffic governing device to its normal position is prevented until the last car or train has cleared the crossing.

Other features, objects and advantages embodying my invention will appear as the specification progresses.

I shall describe one form of apparatus embodying my invention, and shall then point out the novel features thereof in claims.

Referring to the accompanying drawing, which is a diagrammatic view showing one form of apparatus embodying my invention, the reference character GC designates a grade crossing of an east-west railroad EW with a north-south railroad NS. The east-west road is an electrified road over which traffic normally moves in the direction indicated by an arrow, and which is provided with a trolley wire TW. This trolley wire is, of course, connected to a source of propulsion current such as, for example, a 600 volt generator not shown, and the track rails 1a and 1b of the railroad are included in the return path for the propulsion current. In the drawing the trolley wire TW is shown positioned outside

of the track rails for the sake of clarity, but in practice the trolley wire will usually be disposed above the center line of the track rails. It is to be understood that the invention is not limited to a grade crossing.

The railroad EW is provided with a fixed signal S and a derail DR for governing traffic over the crossing GC. Signal S may be of any standard form and is shown as a two-position light signal having a stop lamp 3 and a proceed lamp 4. Derail DR may be of any suitable type and is shown as a single point derail disposed in rail 1b at a location to the left of the crossing and a little in advance of signal S, the distance of 5 the derail from the grade crossing being sufficient to assure that a derailed car will come to a stop before entering the crossing. Derail DR is operated by a motor operated mechanism OM and which mechanism is shown as comprising a 10 double solenoid whose plunger is operatively connected to the movable point of the derail by a suitable drive connection indicated by a dotted line 5. A circuit controller contact member 6 is also operatively connected to the derail through 15 the operating mechanism. The arrangement is such that energization of a normal magnet N of the mechanism positions the plunger to move the detail DR to its open or derailing position and to move contact member 6 to engage a stationary contact 7, and energization of a reverse magnet R of the mechanism positions the plunger to move the derail to its closed or non-derailing position and to move the contact member 6 to engage a stationary contact 8. The 20 mechanism OM is of such construction that it remains in the position to which it was last moved when both magnets N and R are deenergized.

The positions of the derail and of the mechanism OM are repeated by two relays NWP and RWP, relay NWP being energized over an obvious circuit including contact 6—7 to repeat the open position of the derail and relay RWP being energized over an obvious circuit including contact 6—8 to repeat the closed position of the derail.

The magnets N and R of the operating mechanism OM are energized by circuits which are controlled by a contactor 9 and two control relays NW and RW, and which circuits receive energy from the propulsion current source. A circuit is formed for magnet N from trolley wire TW through wire 10, front contact 17 of contactor 9, front contacts 18 and 19 in series of relay NW, wire 20, winding of magnet N and wire 16 to

rail 1a; and a circuit is formed for magnet R from trolley wire TW through wire 10, front contact 17 of contactor 9, front contacts 21 and 22 in series of relay RW, wire 23, winding of magnet R and wire 16 to rail 1a. The contactor 9 is normally energized by current supplied from the trolley wire through wire 10, back contacts 11 and 12 in series of relay RW, back contacts 13 and 14 in series of relay NW, winding of contactor 9, resistor 15 and wire 16 to rail 1a. The contactor 9 is slow to release and consequently when relay NW is energized and picked up, magnet N is energized during the slow release period of contactor 9 to operate the derail to its open position, and when relay RW is energized and picked up the magnet R is energized during the slow release period of contactor 9, to operate the derail to its closed position. The manner of controlling the two relays NW and RW will appear hereinafter.

The railroad EW is provided with three traffic governed devices C1, C2 and C3, and these devices are preferably trolley contactors. Contactor C1 includes two contact members 24 and 25, contactor C2 includes a contact member 26, and contactor C3 includes a contact member 27. Each of these contact members is spaced from the trolley wire to be normally free from contact therewith, but a trolley wheel bridges between the trolley wire and the contact member so that current from the trolley wire passes to the contact member and thence to any circuit connected with such contact member. The two contact members 24 and 25 of contactor C1 are positioned for contact member 24 to be the first to receive current when a car is moving in the normal direction of traffic, and contact member 25 to be the first to receive current when a car is moving against the normal direction of traffic. The contactor C1 is located at a preselected point some distance in the rear of signal S; contactor C2 is located adjacent signal S and contactor C3 is located at a point on the side opposite of the crossing from the derail. The locations of contactors C1 and C3 form a control section for the road EW, the location of contactor C1 being the entrance end of such control section for traffic moving in the normal direction, and the location of contactor C3 being the exit end of such section.

A directional means comprising two relays A1R and A2R is controlled by the contactor C1 to distinguish between cars entering the control section to approach the crossing and cars leaving the control section when moving against the normal direction of traffic to recede from the crossing. Also a car that enters the control section to approach the crossing and then reverses its direction and backs out of the control section is detected by such directional means. Each relay A1R and A2R is provided with a pick-up and a stick circuit, and which circuits receive current from the trolley wire. The pick-up circuit for relay A1R is from contact member 24, through wire 28, back contact 29 of relay A2R, winding of relay A1R, resistance 30 and wire 31 to rail 1b. The stick circuit for relay A1R is from contact member 25, through wire 32, front contact 33 of relay A1R and thence the same as the pick-up circuit to rail 1b. Similarly, a pick-up circuit for relay A2R is from contact member 25, through wire 32, back contact 34 of relay A1R, winding of relay A2R, resistance 30 and wire 31 to rail 1b; and its stick circuit extends from contact member 24 through wire 28, front contact 35 of relay A2R and thence the same as the pick-up circuit

for that relay to rail 1b. A resistance 36 is connected across the winding of relay A1R through front contact 37 of that relay, and is connected across the winding of relay A2R through front contact 38 of that relay, so that each relay A1R and A2R has a slow release characteristic the period of which is predetermined by the resistance 36. It is to be seen, therefore, that relay A1R is energized and picked up when a car moving in the normal direction enters the control section, and that relay A2R is energized and picked up when a car moving in the opposite direction leaves the control section, and that each relay A1R and A2R when picked up is retained picked up for a predetermined slow release period subsequent to the car passing beyond the contactor C1.

Contactor C2 governs a relay BR which is included in a circuit extending from contact member 26 of contactor C2 through resistance 39, winding of relay BR and wire 16 to the track rails. Contactor C3 governs a relay C3R which is included in a circuit extending from contact member 27 of the contactor through the winding of relay C3R, resistance 40 and wire 16 to the rails. Thus when the trolley wheel of a car engages contact member 26 of contactor C2, relay BR is energized and picked up during the period the car is passing the contactor, and when the trolley wheel of a car engages contact member 27 of contactor C3, the relay C3R is energized and picked up. Relay C3R is made slow to release by a resistance 41 connected across the winding of the relay through front contact 42 of the relay.

The relays A1R, A2R and C3R jointly control a counting relay CR to count the number of cars moving into the control section and to require that the same number of cars be counted out of the section before traffic on road NS can be permitted to enter the crossing GC. Counting relay CR may be any suitable construction and is shown as of the construction covered by Letters Patent of the United States No. 1,932,020, granted October 24, 1933, to Branko Lazich, for Electrical relays. In the present application, the construction of this relay will be described only to the extent required for a full understanding of my invention. Relay CR comprises two magnets 43 and 47 which operate two ratchet wheels 48 and 49, respectively. These two ratchet wheels are fixed on a shaft 50 which is constantly urged in a clockwise direction by a spiral spring 51 whose outer end is fastened to a spring case not shown and whose inner end is fastened to shaft 50. A latch pawl 55 engages ratchet wheel 49 to restrain movement of the shaft 50 by the spiral spring. Ratchet wheel 48 is driven in a counter-clockwise direction by magnet 46 through a propelling pawl 52 attached to armature 53 of that magnet. The parts are so proportioned that energization of magnet 46 to attract its armature 53 to the left as viewed in the drawing, raises pawl 52 to engage a tooth of the ratchet wheel 48 and rotate the ratchet wheel one tooth against the force of the spiral spring 51. When magnet 46 is deenergized, its armature 53 is drawn to the right by a bias spring 54 and pawl 52 disengages the teeth of the ratchet wheel. The shaft 50 is held at the point to which it has been advanced by the latch pawl 55. Latch pawl 55 is attached to armature 56 of magnet 47, the armature 56 being biased to the left as viewed in the drawing by a spring 57. Energization of magnet 47 to attract its armature 56 lifts the latch pawl 55 out of engagement with the ratchet

wheel 49 and the shaft 50 is rotated clockwise by spring 51, the rotation of shaft 50 being limited to one tooth by a pawl 58 also attached to armature 56 and raised to engage the ratchet wheel 49 when the armature 56 is attracted by energization of magnet 47. When magnet 47 is subsequently deenergized, the latch pawl 55 drops back to engage the ratchet wheel 49 and restrains further rotation. Thus energization of magnet 46 steps the shaft 50 in one direction and energization of magnet 47 steps the shaft in the opposite direction. Carried on shaft 50 is a contact member 59 which normally is positioned to engage a stationary contact 60 to complete an electrical connection therewith. An energizing impulse supplied to magnet 46 to rotate ratchet wheel 48 and in turn shaft 50 one step causes contact member 59 to be advanced one step away from contact 60 to open the electrical connection therewith. The subsequent energization of magnet 47 serves to rotate the shaft 50 and in turn the contact member 59 back one step for contact member 59 to engage the contact 60. It follows that if magnet 46 is successively energized two or more times, the magnet 47 must be successively energized an equal number of times to reclose the contact 59—60.

Magnet 46 is energized by a circuit from trolley wire TW through resistance 62, front contact 63 of relay A1R, wire 64, winding of magnet 46 and wire 31 to rail 1b. Magnet 47 is provided with a circuit having two alternative paths, one of which passes from trolley wire TW through resistance 62, front contact 65 of relay A2R, wire 66, winding of magnet 47 and wire 31 to the track rail; and the second path of which includes trolley wire TW, wire 40, resistance 67, front contact 68 of relay C3R, wire 69, winding of magnet 47 and wire 31 to the track rail.

A repeater relay APR is controlled by the counting relay CR, relay APR being energized by an obvious circuit including contact 59—60 of relay CR. Hence, when relay CR is energized to step contact member 59 away from its normal position due to a car entering the control section, the repeater relay APR is deenergized, and when relay CR is energized to step the contact member 59 back to its normal position due to the car leaving the control section either at the exit end or by reversing its movement to leave at the entrance end, the repeater relay APR is reenergized. Furthermore, if two or more cars are counted into the control section an equal number of cars must be counted out of the section before contact 59—60 is closed.

Relays BR and C3R jointly control another repeater relay BPS, relay BPS being provided with a pick-up circuit including front contact 43 of relay C3R, and with a stick circuit that includes back contact 44 of relay BR and its own front contact 45. Consequently, when a car moving in the normal direction of traffic passes contactor C2, the repeater relay BPS is deenergized and released, and as this car passes contactor C3 to pick up relay C3R, the repeater relay BPS is reenergized and then retained picked up by its stick circuit. The repeater relays APR and BPS serve to control the control relays NW and RW and the signal S, as will appear presently.

In describing the operation of the apparatus, I shall assume that a car moving in the normal direction of traffic approaches the grade crossing. Relay A1R is energized and picked up as the trolley wheel of the car engages the contact member 24 of contactor C1, and is then released

- at the end of its predetermined slow release period after the car passes beyond the contactor. Magnet 46 of the counting relay CR is energized during the interval relay A1R is picked up, and relay CR is operated to advance its contact member 59 one step to open the contact 59—60 and deenergize the repeater relay APR. With relay APR released closing back contact 70, current is supplied to lamp 3 of the signal S and that lamp is illuminated to display a stop indication. This circuit for lamp 3 can be traced from terminal B through back contact 70 of relay APR, front contact 71 of relay BPS, back contact 72 of repeater relay RWP, lamp 3 to terminal C. 10 The release of relay APR to close its back contact 73 completes a circuit for the control relay RW, current flowing from terminal B through back contact 74 of relay RWP, a contact 75 controlled by traffic on road NS and closed only 15 when there is no train within definite limits approaching the crossing on road NS, back contact 73 of relay APR and winding of relay RW to terminal C. Relay RW is now picked up to energize magnet R and operate the derail to its non-derailing position. When the derail is closed, the repeater relay RWP is energized and repeater relay NWP is deenergized. With relay RWP picked up to open back contact 72 and close its front contact 76, the circuit for lamp 3 20 of signal S is opened and the circuit for lamp 4 is closed and signal S displays a proceed indication. As this car moves past contactor C2 at signal S, the relay BR is momentarily energized and picked up to cause the release of repeater relay BPS. Relay BPS upon releasing to open front contact 71 and close back contact 77 opens the circuit for proceed lamp 4 and closes a circuit for stop lamp 3 and signal S displays a stop indication. When this car advances over the 25 grade crossing, and its trolley wheel engages contact member 27 of contactor C3, relay C3R is energized causing the repeater relay BPS to be reenergized. Relay C3R on being energized to close front contact 68, also completes the circuit for magnet 47 of the counting relay CR and that relay is operated back to its normal position to close contact 59—60 and cause repeater relay APR to be reenergized. A circuit is now formed from terminal B through back contact 78 of 30 relay NWP, front contact 79 of relay APR, winding of relay NW and terminal C, and relay NW is energized. With relay NW picked up the magnet N is energized to operate the derail to its open position and causes repeater relay NWP to be energized and relay RWP to be deenergized 35 and the apparatus is restored to its normal position. 35 In the case a second car follows the first car into the control section, the second car causes counting relay CR to be operated a second step away from its normal position so that when the first car moves out of the control section at contactor C3, the contact member 59 of relay CR is still one step away from its normal position, 40 and repeater relay APR remains deenergized with the result that the derail remains at its closed position, and signal S is operated as required to display its proceed lamp 4 for the second car. When this second car advances over 45 the crossing and past the contactor C3 to cause relay C3R to be again picked up, the counting relay CR is again energized to step its contact member 59 back to the normal position, so that the derail DR is then operated to its open position and signal S is set to display a stop indica- 50 55 60 65 70 75 80 85 90 95

tion: That is to say, the same number of cars that enter the control section must be counted out of the control section before the derail DR and signal S are conditioned to permit use of the grade crossing by traffic on the road NS. In this connection it is to be noted that the repeater relay NWP controls at its front contact 80 a circuit for governing the signals for the road NS, and hence the grade crossing is released for use by a train on road NS only when the derail DR is set at its derailing position.

In case a car moving in the normal direction of traffic passes contactor C1 and operates relay CR to bring about the closing of derail DR and the display of a proceed indication at signal S and such car then reverses its direction and backs away from the crossing, the movement of the car past contactor C1 energizes relay A2R, causing relay CR to be energized to step the contact member 59 back to its normal position so that the derail DR and signal S are restored to their normal positions.

It is to be seen from the foregoing description that I have provided apparatus for automatic control of derails and similar traffic governing devices at a grade crossing and similar hazardous points and wherewith track circuited track sections are not required.

Although I have herein shown and described but one form of railway traffic controlling apparatus embodying my invention, it is understood that various changes and modifications may be made therein within the scope of the appended claims without departing from the spirit and scope of my invention.

Having thus described my invention, what I claim is:

1. In combination, a railroad over which traffic normally moves in a given direction and which uses a trolley wire, a derail located in said railroad, a signal located just to the rear of said derail; a first, a second and a third trolley contactor which are located at a point to the rear of the derail, adjacent said signal and at a point in advance of the derail respectively; a counting relay having a contact member operable in a step-by-step manner away from or toward a normal position according as the relay is energized at a first sense or energized at a second sense, means including said first contactor to energize said relay at said first sense when a car passes that contactor, means controlled by said contact member and by a contact closed under safe traffic conditions to energize said motor means to operate the derail to a non-derailing position when the contact member is stepped away from its normal position, other means governed by said contact member to control said signal to a proceed position when the contact member is stepped away from its normal position, means including said second contactor to remove said contact member from control of said other means and to establish a stop position for said signal when a

car passes the second contactor, and means including said third contactor to energize said counting relay in said second sense and to restore the control of said contact member over 5 said other means.

2. In combination with a hazard along a railroad over which traffic normally moves in a given direction and which uses a trolley wire, a derail located at a point to the rear of said hazard, 10 motor means connected to said derail for operation thereof, a signal energizable to display either a stop or a proceed indication but normally deenergized and located just to the rear of said derail; a first, a second and a third trolley contactor which are located at a point some distance to the rear of the derail, adjacent said signal and at a point in advance of said hazard respectively; a first circuit means including said first contactor and a contact closed under safe traffic 15 conditions at said hazard to energize said signal to display its stop indication and to energize said motor means to operate the derail to its non-derailing position when a train passes that contactor, means controlled by said derail to change the energization of said signal to display its proceed indication when the derail is at its non-derailing position, a second circuit means including said second contactor to energize said signal to display its stop indication when said train passes that contactor, 20 25

3. In combination, a railroad over which traffic normally moves in a given direction and which uses a trolley wire, a fixed signal located a pre-selected point to the rear of a fixed hazard and energizable to display either a stop or a proceed 30 indication and normally deenergized; a first, a second and a third trolley contactor located at a point some distance to the rear of said signal, adjacent said signal and at a point in advance of the hazard respectively; a first circuit means including said first contactor to energize said signal to display its stop indication when a train passes that contactor, a second circuit means controlled by said hazard when conditioned for safe passage of traffic to cooperate with said first 35 circuit means to energize said signal to display its proceed indication, a third circuit means including said second contactor to energize said signal to display its stop indication when the train passes that contactor, a fourth circuit means including said third contactor to deenergize said signal when the train passes that contactor, and means including a counting relay 40 controlled by a train passing said first contactor to render said fourth circuit means ineffective to deenergize said signal when another train passes said first contactor prior to the first mentioned train passing said third contactor.

PAUL P. STOKER.
